(57) **CLAIM**

I claim the ornamental design for an oil filter removal tool, as shown and described.

DESCRIPTION

FIG. 1 is a perspective view of an oil filter removal tool showing my new design.

FIG. 2 is a front elevation view of the oil filter removal tool shown in FIG. 1.

FIG. 3 is a rear elevation view of the oil filter removal tool shown in FIG. 1.

FIG. 4 is a right side elevation view of the oil filter removal tool shown in FIG. 1.

FIG. 5 is a left side elevation view of the oil filter removal tool shown in FIG. 1.

FIG. 6 is a top plan view of the oil filter removal tool shown in FIG. 1; and,

FIG. 7 is a bottom plan view of the oil filter removal tool shown in FIG. 1.

The ornamental design which is claimed is shown in solid lines in the drawings. Broken lines, if present in the drawings, are for illustrative purposes only and form no part of the claimed design.

1 Claim, 7 Drawing Sheets
